UNITED STATES PATENT OFFICE.

DAYTON H. CREWS, OF IOWA PARK, TEXAS, ASSIGNOR OF ONE-HALF TO
JAMES I. FAISON, OF SAME PLACE.

EXTENSION-BRACE FOR LADDERS.

SPECIFICATION forming part of Letters Patent No. 495,108, dated April 11, 1893.

Application filed May 23, 1892. Renewed March 14, 1893. Serial No. 465,968. (No model.)

To all whom it may concern:

Be it known that I, DAYTON H. CREWS, a citizen of the United States, residing at Iowa Park, in the county of Wichita and State of 5 Texas, have invented a new and useful Extension-Brace for Ladders, of which the following is a specification.

This invention relates to certain new and useful improvements in extension ladders, 10 and has special reference to extension braces for such class of ladders, and consists of an improvement on the construction and arrangement of parts as set forth in my application for patent bearing Serial No. 416,418, filed 15 September 29, 1891, and allowed April 27, 1892, as will be more fully hereinafter described and claimed.

The object of this invention is to provide an extension brace for extension ladders in 20 which the parts composing the same are positively raised and lowered by means of direct acting mechanism which is so constructed and arranged as to obtain the most beneficial results from a comparatively small application of power, the parts being strong and durable easily operated and readily understood.

In the drawings:—Figure 1 is a perspective view of a ladder showing improved construction in connection therewith. Fig. 2 is 30 a side elevation of the same, broken away. Fig. 3 is a front elevation of the brace operating mechanism.

Similar numerals of reference are employed to indicate corresponding parts in the several 35 figures.

Referring to the drawings, the numeral 1 designates the ladder section which is at the bottom and is adapted to receive extension sections 2 and 3, which are supplied with operating mechanism 4, 5 and 6 as fully set forth in my aforesaid application and adapted to be actuated to extend or withdraw the several ladder sections as will be understood. To the upper portion of the bottom or lower 45 ladder section 1 is secured a brace or connection 7, consisting of side bars 8, connected to the side rails of said ladder section and having cross strips 9 connecting the same. To the central portion of the cross strips 9, is 50 secured the upper end of a brace 10, having teeth 11 on the lower portion thereof and a

stop block or projection 12 above the said teeth, the latter being adapted to prevent the downward movement of the said brace beyond a predetermined point. The lower 55 support or rest for the brace 10, consists of parallel bars or strips 13, connected by straps or cross pieces 14, which hold the said bars or strips 13 apart from each other sufficiently to permit the brace 10 to freely move between 60 the inner opposing edges thereof and inside of the straps or cross pieces 14 to be placed against opposing sides of the bars or strips 13 at the upper and lower portions of the same for an evident purpose. Suitable boxes 65 15 are secured on the upper portion of the bar or strips 13 and therein is journaled a shaft 16, having a crank handle 17 at one end, a toothed or gear wheel 18 thereon between the boxes 15, and a ratchet wheel on the end 70 of the same opposite to that to which the crank handle 17 is located, said ratchet wheel 19 being engaged by a pawl 20 adjacently located. The said toothed or gear wheel 18 engages the teeth 11 on the lower portion of the 75 brace 10, and thereby the ladder is raised and lowered when the shaft 16 is suitably operated. The block or projection 12 on the brace 10 is adapted to contact with one of the upper cross strips 14 to limit the movement of 80 the said brace as herein before set forth. The bars or strips 13 are held in elevated position by divergent legs 21 bolted to the lower portions of the same, as at 22 and held in reinforced position by the lower straps or cross 85 strips 14 which are extended outward beyond the bars or strips 13, and secured to said legs. The lower portions of the legs 21 are formed with apertures 23 for adjustment of the sleeves 24. Above the lower ends of the 90 said legs 21 are secured the sleeves 24 having eyes 25, which are adapted to be engaged by the hooked ends of stay rods 26, pivotally connected to the ladder section 1, and adapted to be folded up against said latter section 95 and engaged by spring holding jaws 27, secured to the side rails of said ladder section, and having flaring ends 28 to provide a convenient means of forcing the ends of the said stay rods 26 thereinto. The teeth 11 may be 100 connected to or formed with the brace 10 and other parts of the construction might be

slightly changed without in the least departing from the nature and spirit of the invention. The brace or connection 7 is in the form of a pivoted depending frame, and as the 5 brace 10 is operated, the lower ladder section 1, together with the other sections carried thereby may be suitably inclined and held in adjusted position.

The construction provides for an easy and 10 rapid adjustment of the parts of the ladder and the device as a whole forms an important improvement on the construction shown and described in the aforesaid application.

Having thus described the invention, what 15 is claimed as new is—

1. In a ladder of the character set forth, the combination of a lower ladder section, a brace connected thereto and having teeth thereon, a support consisting of parallel bars between 20 which the said brace has movement, a shaft carrying a toothed wheel to engage the teeth with the said brace and having a ratchet and pawl mechanism in connection therewith, divergent legs connected to said support and 25 stay rods detachably secured to said legs and carried by the said ladder section, substantially as described.

2. In a ladder of the character set forth, the

combination of a lower ladder section, a depending frame pivotally connected to the upper part of said ladder section, a brace connected to said frame and having teeth thereon, a support having parallel bars with cross strips for connecting pieces between which the said brace has adjustable movement, a 35 block or projection on said brace to limit the movement thereof, a shaft carried by said support having a toothed or gear wheel thereon adapted to engage the teeth of the brace, and ratchet and pawl mechanism in connection with the same, divergent legs having lower adjustable sleeves above the ends of the said legs and having eyes in connection therewith, stay braces having hooked ends engaging said eyes of the sleeves and pivotally carried by the ladder section and spring holding devices carried by the said ladder section with which the said stay rods are adapted to engage, substantially as described.

In testimony that I claim the foregoing as 50 my own I have hereto affixed my signature in the presence of two witnesses.

DAYTON H. CREWS.
